Filed Dec. 17, 1959, Ser. No. 860,187

Claims priority, application Great Britain Aug. 4, 1959
2 Claims. (Cl. 114—126)

This invention relates to ship stabilizers of the kind in which fins or hydrofoils projecting from the hull of a ship below the water-line are tilted or oscillated to react with the water when the ship is in forward motion in such a way as to produce a torque which continuously opposes the torque due to sea force causing the ship to roll.

The present invention particularly relates to a ship stabilizer system of the kind comprising a plurality of small fins attached to the ship in the region of the bilge, each fin being provided with an integral actuating means, the motion of said actuating means being governed by a common roll-sensing means.

A feature of the invention is the use, in the construction of the fins, of various moulding techniques and materials.

In one construction the fin mounting member, which may be a shaft adapted to rotate in a bearing or, alternatively, a bearing part adapted to rotate round a fixed shaft, is extended laterally to form a skeleton or framework for supporting the fin. The fin itself is made from an elastomer, for instance, rubber, polyvinyl chloride or similar substance moulded around and in intimate contact with the supporting framework. The framework is deliberately kept to a minimum size both in chord length and outreach with the object of making the fin resilient against overload forces such as may be encountered if the ship is proceeding in water such as harbours and estuaries which may be fouled by floating or submerged objects or should the ship make contact with the ground or a river bank or with another ship. Under the normal forces of fin lift and drag imposed on the fin due to passage through the water, its shape is not significantly altered, but under direct impact it yields to the force of the impact and so reduces the risk of damage.

The fin shaft or, alternatively, the shaft on which the fin is adapted to rotate, may be constructed with a section of reduced diameter to act as a safety device by limiting the force that may be imposed on the ship in the event of impact of a fin or fins with a solid object by permitting the fin or fins to break off.

In a still further construction a fin may be moulded to the correct form around a metal center or insert in hard-setting materials such as fibreglass and nylon. In fin construction and the hydraulic actuators co-operating therewith all metal parts coming in contact with the sea water may be fabricated from non-corrodible metal, for instance, stainless steel, bronze and Monel metal. Bearing surfaces and particularly those employing water lubrication may alternatively be made of Tufnol (Registered Trade Mark), nylon, polytetrafluoroethylene or similar materials. In small equipments the fins may be constructed of wood.

Another feature of the invention is the adoption of a rotary hydraulic jack or vane motor as the fin actuating means. This device is cheap to manufacture, takes up little space and is easily integrated into the fin construction.

A further feature is a locking device to hold the fin in a neutral position with respect to the water flow when not required for active stabilizing. For this purpose the fin is pivoted forward of its center of pressure so that when

2

not controlled by the actuating means it will automatically assume the neutral position. However, to maintain the fin in neutral position when the ship is stationary a spring-loaded and hydraulically operated bolt co-operating with a catch or detent is provided. When the stabilizer is in operation the bolt is withdrawn from the catch by hydraulic pressure opposing the spring pressure. But when the stabilizer is stopped the hydraulic pressure is released and the spring urges the bolt in the direction of the catch. As soon as the water flow aligns the fin in the neutral position the bolt enters the catch and the fin is locked against further movement. The fins then function as a bilge keel giving passive roll damping.

The invention also consists in a stabilizing arrangement for ships comprising a set of fins on each side of the ship in which the proportional control of the stabilizing force is effected by operating the fins sequentially to their maximum angle of tilt.

The invention will be further described with reference to the accompanying drawings in which:

FIGURE 1a is a side elevation and

FIGURE 1b is a cross-section of a flexible fin construction.

FIGURE 2a is a longitudinal section and FIGURE 2b 25 a cross section on the line A—A of FIGURE 2a and FIGURE 3a is a plan in partial section.

FIGURE 3b is an elevation and

FIGURE 3c a section on the line B—B of FIGURE 3b of a hydraulic control device.

30 FIGURE 4 shows diagrammatically a ship stabilizer system employing hydraulic actuating means with oil as the hydraulic fluid.

FIGURE 5 is a diagrammatic plan view of the ship's hull showing its relationship to part of FIGURE 4 in 35 one arrangement.

FIGURE 6a is a graph showing the operation of the arrangement of FIGURE 5 for light rolling, and

FIGURE 6b is a similar graph for heavy rolling.

FIGURE 7 is a ship stabilizer system similar to that 40 shown in FIGURE 4 but using sea water as the hydraulic fluid.

FIGURE 8 shows a modification of part of FIGURE 4.

FIGURE 9 is a frontal view of an alternative cam actuated by the device sensitive to rolling of the ship, 45 and

FIGURE 10 shows diagrammatically the operation of a hydraulic relay system connecting the fins with the cam.

FIGURE 11 is a diagrammatic showing of a six fin 50 stabilizer corresponding to FIGURE 5 but activated by the alternative means of FIGURE 9.

In FIGURE 1a the fin shaft 1 bearing fin 2 is rigidly attached to the ship structure 3 by flanges 4. Hydraulic actuating means which may be of the rotary jack or vane motor kind is located within the annulus 5a between fin 55 shaft 1 and fin sleeve 5. Fin sleeve 5 terminates about half-way along the rotational axis of the fin 2 and is formed with lugs 6 and 7 conforming to the streamline section of the fin. The fin proper is moulded from suitable plastic material such as vulcanised rubber or polyvinylchloride to the correct fin contours and completely surrounds the outboard end of the fin sleeve and the lugs 60 6 and 7. It will be seen from the construction that the inner part of fin 2 is given the support of fin sleeve 5 and lugs 6 and 7 whereas the outer part of the fin between x and x' is not reinforced. This outer part, however, is sufficiently rigid to withstand the normal forces of lift and drag but it will yield to abnormal forces due to contact with floating objects or grounding.

A hydraulic jack or rotary vane motor according to 70 the invention is shown in FIGURES 2a and 2b. Shaft 8 which also forms the stator element of the rotary vane motor is attached to ship structure 3. Part 9 is rotatably

mounted on shaft 8 and forms the rotor of the vane motor and also supports fin 2. By means of annular ring 10 screwed to shoulder 11 on the stator part 8 and annular ring 12 abutting shoulder 13 on the stator part 8 and bolted to it, and also abutting a shoulder on part 9 an annular space or chamber 14 is formed between the stator and the rotor. This chamber is sealed by O-rings 15 and 16. Annular rings 10 and 12 abut adjacent shoulders on the inside surface of rotor part 9 as shown in the drawing thereby providing a positive location of rotor part 9 on stator part 8. Vanes or lands 17 and 18 attached to rotor part 9 and corresponding vanes or lands 19 and 20 attached to stator part 8 divide chamber 14 in four compartments *a*, *a*₁, *b*, *b*₁. Compartments *a* and *a*₁ are connected to the hydraulic pressure source over channel 21 and channel 22 while compartments *b* and *b*₁ are connected to exhaust over channel 23 and channel 24. It will be appreciated that when pressure oil is admitted to chambers *a* and *a*₁, these chambers will expand by forcing vanes 17 and 18 to rotate in a clockwise direction as viewed in FIGURE 2b until arrested by resilient stops 25. At the same time, oil contained in chambers *b* and *b*₁ which are contracting is exhausted over channels 23 and 24. It is easily seen that when oil is admitted to chambers *b* and *b*₁ the reverse sequence of events takes place. Resilient stops 25 and 26 comprise coil springs of wire or strip material such that by slight deformation of their cylindrical form, they absorb the shock of impact at the end of travel of the moving vanes.

The fin locking device comprises piston 27 operating in cylinder 28. Spring 29 in the lower portion of cylinder 28 urges piston 27 and bolt 30 attached thereto into engagement with slot 31 in rotor part 9 indicated by broken lines thereby securely locking the fin. The travel of the bolt is limited by perforated collar 32 coming up against shoulder 33 in stator part 8. Application of pressure oil to the top side of piston 27 over channel 23a forces bolt 30 out of engagement against the pressure of spring 29 and so releases the fin for rotary motion. Extension 34 of piston 27 limits the travel of the bolt in the downwards or outwards direction.

FIGURES 3a, 3b and 3c show a hydraulic valve unit embodying a plurality of valves of the piston type adapted for fin operation. The cylinder block 35 in which a number of cylinders 36 are bored comprises a solid block 45 of metal. Ports 37 in cylinders 36 are connected over pipe lines to hydraulic actuators in their respective fins as shown in FIGURE 4. High pressure oil is supplied over duct 38 to ports 39 in each cylinder. The tops of cylinders 36 are closed by plate 40 provided with holes 41 registering with the axes of each cylinder. The bottoms of said cylinders are closed with another plate 42 provided with holes 43 also registering with the axes of the cylinders.

The action of a valve may best be explained with reference to FIGURE 3c in which piston 44 is shown in the normal or unoperated position at the top of its stroke urged thereto by spring 45. Piston 44 has an extension 46 passing through hole 41 and terminating in adjustable tappet head 47. Pressure oil is fed to the cylinder over duct 38 and port 39. Port 37 is in communication with one side of a hydraulic actuator which may be of the forms shown in FIGURE 2a or FIGURE 10 (not shown) over pipe 48. When tappet 47 is depressed so that land 49 of piston 44 is below port 37, pressure oil passes to the hydraulic actuator and causes the fin to proceed to full tilt. Releasing the tappet causes piston 44 to return to its original position, urged thereto by spring 45 so that pressure is released in the hydraulic actuator and the pressure oil may exhaust through port 43 as the fin returns automatically to the neutral position in aligning itself with the streamline water flow. It will be seen that after land 49 has uncovered port 37 the piston may travel further in a downwards direction while still maintaining the oil supply to the hydraulic actuator. This feature will

be seen to be necessary to the proper functioning of the stabilizer as will be described hereinafter.

In FIGURE 4 a roll sensing device 50 of known kind which may embody a rate gyroscope to detect the velocity of roll has an output shaft 50a which operates tilting arm 51 by lever 52 and link 53. Hydraulic valve units 35 and 36 of the kind shown in FIGURES 3a, 3b and 3c are disposed to co-operate with extensions 56 and 57 of rocking lever 51. The said hydraulic valve units are partly immersed in a tank 58 of hydraulic fluid such as oil. Said hydraulic fluid is drawn from tank 58 by pump 59 driven by electromotor 60 and passed at high pressure to ducts 38 (FIGURES 3a, 3b and 3c) over pipe 61.

Outlet ports of valve unit 35 are connected in sequence over pipe lines 48 to one side of the appropriate fin actuator and each outlet port of valve unit 35 is similarly connected to the other side of the fin actuators over pipe lines 68.

Conveniently, each pipe line may include a shut-off valve 63 and a fluid flow indicator 64. Pipe lines 62 extend from the high pressure side of pump 59 to the bolt actuating cylinders associated with each fin. When the stabilizer is in operation high pressure fluid in pipelines 62 retracts the bolts in the said bolt actuating cylinders thereby allowing free movement of the fins. It will be appreciated that when the stabilizer is put out of action, as by stopping the pump 59, the pressure in the pipelines 62 will be removed and the bolts will engage the slots in the fin urged thereto by spring pressure as hereinbefore explained. Six valves are shown in the figure. This would correspond to an installation having three fins on each side or six fins on one side, or as desired. Larger numbers of valves may be employed. For a larger installation fins may be operated in pairs or other groups from one valve.

FIGURE 5 shows one arrangement of the stabilizer employing six fins actuated to progressively counter the roll of a ship. The six fins *a*-*f* are arranged in a symmetrical manner as shown in the figure, each fin being actuated by a hydraulic motor connected over pipe lines 48 to hydraulic valves *a*' to *f*' respectively and over pipe lines 48 to hydraulic valves *a*'' to *f*'' respectively. Thus it will be seen that as extension 56 of tilting arm 51 descends the said fins will be operated to full tilt in the following sequence, the signs indicating the incidence or lift of the fins: *a*+, *b*-, *c*+, *d*-, *e*+, *f*-. When extension 56 has completed its movement three fins on one side of the ship have been tilted to positive incidence and three fins on the other side to negative incidence, all fins combining to produce a torque in one direction. It will be further seen that as extension 56 returns to the central or neutral position the fins will return to their neutral positions in reverse sequence. Now when the extension 57 descends the fins will be operated to full tilt in the sequence *a*-, *b*+, *c*-, *d*+, *e*-, *f*+, and as said arm returns to neutral the fins will again return in reverse sequence to their neutral position. Tappets 47 may be adjusted to provide a smooth transition from one sequence to the other.

The movement of tilting arm 51 is controlled by a sensing device of known kind responsive to the roll velocity and FIGURES 6a and 6b illustrates by graphs the action of the fins for one complete oscillation or roll of the ship assuming the roll to be sinusoidal.

In FIGURE 6a, curve A represents the magnitude of the roll angle plotted against time and curve B (which corresponds to roll velocity) the magnitude of the fin power (as expressed by the number of fins in action) to counter the roll, in circumstances where the fin power or torque is just sufficient to balance the rolling torque. It will be understood that for light rolling in moderate seas less than the maximum number of fins will be brought into operation to counter the reduced roll. When, however, the magnitude of the roll, and consequently the roll torque, exceeds the maximum fin power or torque all of

the fins will proceed to their tilted positions to develop maximum fin power in the time that the roll torque builds up to a corresponding value and all the fins will remain fully tilted until later, the roll torque falls to the value of the fin torque. This is shown by the graphs in FIGURE 6b where the hatched area represents fin torque.

It must be understood that the fins may be any in number, they may be arranged differently, for example, all on one side of the ship, and they may operate in various sequences since such variations will not effect or alter the fin torque law as represented in FIGURES 5 and 6a and 6b. Furthermore, a signal responsive to other derivatives of the roll, for example, acceleration and displacement, may be introduced into the fin control signal in known manner to improve the efficiency of the stabilizer for non-sinusoidal roll displacements.

Various sequences of operation of the fins may be arranged depending on the manner in which the hydraulic valves are connected to the fin actuators. The underside or operating faces of rocking arm extensions 56 and 57 as shown in FIGURE 3 are flat. Using this configuration and by adjusting the heights of the tappets 47 (FIGURE 3) in an appropriate manner the valves may be made to operate according to a linear sequence. By changing the contour of the operating faces and/or the heights of the tappet, sequences obeying other laws may be arranged.

The sequence of operation of the fins to counter a roll to port may, if desired, be different from the sequence to counter a roll to starboard.

FIGURE 7 shows a construction in which sea water is used as the hydraulic fluid.

Pump 59 driven by electromotor 60 draws sea water through filter 65 and passes it under pressure to valve units 35 and 35'. Low pressure exhaust water from the fin actuators is collected in tank 58 and flows by gravity back to the sea via pipe 66.

It is sometimes advantageous to introduce an element of control whereby the number of fins in operation is reduced with increased speed of the ship.

FIGURE 8 illustrates the manner in which this type of control may be adjusted to the stabilizer according to the present invention.

In this figure, box 69 represents the control sensitive to ship speed, output rod 70 being adapted for linear movement related to ship speed. Roll sensing device 50 operates tilting arm 51 over lever 52 and link 53 as previously described but in the present construction lever 71 and link 72 are interposed between lever 52 and link 53. Lever 71 is provided with a slot in which fulcrum 73 attached to output rod 70 is slidably mounted.

Thus for a given movement of lever 52, the amount by which arm 51 is tilted, and consequently the number of fins brought into operation is dependent upon the position of fulcrum 73, which in turn is dependent on ship speed.

FIGURES 9, 10 and 11 show an alternative fin operating arrangement wherein cam means are caused to rotate fin hydraulic control valves of the known 3-position kind and the fins are actuated by piston means.

As shown in the FIGURES 9 and 10, the cam 74 is carried on the shaft 50a and is provided with a radial face having three steps 74a, 74b and 74c. The middle step b corresponds to the neutral position of the fins, whilst one of the other steps a or c corresponds to a tilting upwards of the fins on one side of the ship and in the opposite direction on the other side of the ship, and the third step corresponds to a tilting of fins opposite to this. Six spring-loaded rods 75 are provided for actuating six three-way valves 76 one of which is shown in FIGURE 10.

The valve 76, when operated by push rod 75, can allow liquid arriving from the pump or reservoir by a supply pipe 77 to flow into a pipe 78 or a pipe 79. When in the neutral position shown, both pipes are connected to exhaust. The pipes 78 and 79 are fitted with locking valves 75

80 and 81 and thence lead to the position in the bilge keel where the corresponding fin is mounted.

FIGURE 10 shows a fin operating means alternative to that shown in FIGURES 2a and 2b namely, hydraulic jacks comprising two pistons or plungers contained in corresponding cylinders in a cylinder block. The cylinder block may be attached to the fin, the pistons reacting with an attachment to the fin pintle as shown. Alternatively, the cylinder block may be attached to the fin pintle, the pistons reacting with an abutment of the fin. In the figure, pipes 78 and 79 are connected with the two hydraulic jacks 82 and 83 mounted in the fin by two flexible pipes 84 and 85. The plungers 86 and 87 of the jacks are arranged to abut against the ends of a thrust block 88 fixed integrally on the fin pintle 89.

All the valves controlled through push rods 75 are connected with fins on one side of the ship.

FIGURE 11 shows a six-fin stabilizer corresponding to that of FIGURE 5 but actuated by the alternative means.

In the figure in which like references represent like parts where applicable the cam 74 is represented for clarity of presentation as a linear device having identical cam faces on each side. Such a cam device may be alternatively used where the output from the control is a linear motion. Pipes 78 and 79 lead directly to the fin hydraulic jacks on one side of the ship while pipes 78 and 79 leading to the fin hydraulic jacks on the other side of the ship are crossed over. The stabilizer functions in the following manner: When all the rods 75 rest on step 74b of cam 74, valves 76 are in the neutral or central position and the corresponding fins occupy neutral or horizontal positions by virtue of the flow of water over them as previously explained. When cam 74 moves downwardly rods 75 progressively rise onto step 74c and the left-hand fins in the figure tilt in one direction and because pipes 78 and 79 are crossed, the right-hand fins are tilted in the opposite direction to the fins on the left to add to the stabilising torque. When, however, cam 74 moves from the central position upwardly rods 75 progressively descend on to step 74a urged thereto by their respective springs. Valves 76 now move in the opposite direction and consequently the tilt of the fin is reversed.

We claim:

1. A ship stabilizer system comprising a ship's hull, a plurality of stub axles rigidly attached in spaced positions along the hull in the region of the bilge, fins mounted on the stub axles for oscillation about a neutral position, individual hydraulic motors for oscillating the respective fins, hydraulic pump means, hydraulic lines for circulating hydraulic fluid from the pump through the hydraulic motors, individual valve means for controlling the fluid flow from the pump to the respective hydraulic motors, sensing means mounted to respond to roll of the hull, means for operating the valve means in sequence from the roll-sensing means, and means responsive to ship's speed for limiting the number of fins brought into operation.

2. A ship stabilizer system comprising a ship's hull, a plurality of fins attached in spaced positions along the hull in the region of the bilge for oscillation about a neutral position, individual hydraulic motors for oscillating the respective fins, hydraulic pump means, hydraulic lines for circulating hydraulic fluid from the pump through the hydraulic motors, individual valve means for controlling the fluid flow from the pump to the respective hydraulic motors, sensing means mounted to respond to roll of the hull, means for operating the valve means in sequence from the roll-sensing means, and means responsive to ship's speed for limiting the number of fins brought into operation.
